UNITED STATES PATENT OFFICE

2,289,045

OVERHEAD DOOR CONSTRUCTION

Alvin V. Rowe, Galesburg, Ill., assignor to Rowe Manufacturing Company, Galesburg, Ill., a corporation of Illinois

Application June 9, 1941, Serial No. 397,256

5 Claims. (Cl. 20—20)

This invention relates generally to overhead door constructions and more particularly to overhead door constructions wherein hinged door panels are shiftable between vertical door closing position and open overhead position.

It is one of the objects of the present invention to provide an overhead door arrangement equipped with track follower members along opposite margins thereof and guideways cooperating therewith which are so disposed as to greatly facilitate the ease with which certain of the track followers may be guided in a given direction and others guided in a different direction.

More specifically the invention contemplates an overhead door arrangement wherein a plurality of hinged door sections having track followers disposed along opposite side margins, some of which are intermediate and others adjacent the upper and lower margins of the door, are directed along double vertical guideways and a single horizontal guideway.

It is a further object of the present invention to provide in association with hinged door panels and track followers, as set forth above, guideways wherein one of the vertical double guideways is defined on one side by the inner surface of the door jamb.

A further object of the present invention is to provide an overhead door arrangement of the type set forth above wherein the track followers and guideways therefor are so arranged as to enable the installation of the structure in instances where a minimum amount of head room is available. To this end the invention contemplates means associated with the uppermost section for swinging said section into closing relation with respect to the door jamb as the sections approach the limit of their door closing position.

Still more specifically the invention contemplates an overhead door construction wherein track followers associated with the uppermost section and the follower members associated with the hinges of the sections are directed along a given guideway and follower members associated with the lowermost door section are directed along another guideway whereby to facilitate installation and operation of the door sections.

The foregoing and other objects and advantages will be more apparent from the following detailed description when considered in connection with the accompanying drawings wherein—

Fig. 1 is a vertical sectional view of a building equipped with an overhead door construction as

contemplated by the present invention, said view being taken substantially along the line 1—1 of Fig. 2;

Fig. 2 is a transverse vertical sectional view taken along the line 2—2 of Fig. 1;

Fig. 3 is an enlarged fragmentary sectional view taken along the line 3—3 of Fig. 2 showing the door sections in their normal vertical closed position;

Fig. 4 is a fragmentary detailed sectional view of the upper left hand corner of the structure shown in Fig. 3 to illustrate the position occupied by the lowermost door section when it has been shifted to its open overhead position;

Fig. 5 is an enlarged fragmentary horizontal sectional view taken substantially along the line 5—5 of Fig. 3;

Fig. 6 is a fragmentary vertical sectional view taken substantially along the line 6—6 of Fig. 5 to more clearly illustrate the track follower or roller which is directed within the vertical guideway, one side of which is defined by the inner surface of the door jamb;

Fig. 7 is an enlarged fragmentary vertical sectional view similar to Fig. 3 disclosing a modified overhead door arrangement wherein the double guideway is comprised of two adjacently positioned tracks which digress away from the door jamb toward their upper extremities to facilitate travel of the door sections;

Fig. 8 is a fragmentary sectional view similar to Fig. 7 disclosing the door sections shifted to their upper or overhead position; and

Fig. 9 is an enlarged horizontal sectional view taken substantially along the line 9—9 of Fig. 7.

Referring now to the drawings wherein like numerals have been employed to designate similar parts throughout the various figures, it will be seen that the invention contemplates an overhead door construction which includes a plurality of hinged door sections 10, 12, 14 and 16. These sections 10—16 are connected by suitable hinges 18 disposed along opposite margins and each hinge member carries a track follower or roller 20. These track followers 20 are hereinafter referred to as intermediate followers or rollers inasmuch as they are positioned intermediate the upper and lower margins of the door. A track follower or roller 22 is associated at each side of the upper margin of the door and is carried at the free extremity of an arm 24 which is pivotally connected with a bracket 26 secured to the upper door section 10 as clearly illustrated in Fig. 3. A coil spring 28 is interposed between the door section 10 and the arm 24 so as to con-

50

tinually urge said arm to the left as viewed in Fig. 3.

At each side of the lower margin of the door is a guide roller 30 carried by a pintle or stub shaft 32 secured to and extending outwardly from the side margin of the lowermost door section 16 (see Fig. 6). The outer extremity of the pintle or stub shaft 32 is connected to one extremity of a flexible lifting element or cable 34. This flexible lifting element 34 as shown in 10 Figs. 1 and 2 extends upwardly to an idler or sheave 36 and thence rearwardly to a suitable counterbalancing mechanism designated generally by the numeral 37. Inasmuch as the present invention is not particularly concerned with the type of counterbalancing mechanism which may be used, said mechanism is not disclosed in detail and it will suffice to say that any suitable means for counterbalancing the weight of the door sections 10-16 may be employed.

Attention is directed to the fact that the intermediate guide rollers 20 are directed and guided within a substantially vertical track or guideway 38, a connecting curved track portion or guideway 40 and a substantially horizontal track or guideway 42. The roller 22 is also guided within the curved track or guideway portion 43 and the horizontal guideway 42. The roller 30 is directed within a vertical guideway 44 which is defined by the inner surface 46 of the door jamb 48 and the adjacent tread portion 50 of the vertical guide track 38 (see Figs. 3 and 5). As the guide roller 30 moves upwardly within the guideway 44 it eventually moves into the portion thereof which is bounded by the inner surface 46 of the door jamb 48 and a tread portion 52 which extends upwardly from and forms an extension of the tread portion 50 of the vertical guide track 38. The roller 30 eventually comes to rest within a curved track or guideway 54 which extends rearwardly from the guideway 44 as clearly illustrated in Fig. 4. This guideway 54 serves to prevent the lower margin of the door from moving into interference with the sheave wheel 36 as the door sections move suddenly to their overhead position. Associated with the rearward extremity of the guideway 54 is an abutment 56 which limits the extent of rearward movement of the lowermost door section. This abutment 56 is positioned in the path of movement of the roller 30 and hence serves as an abutment therefor. This abutment 56, the structure of the track 54, the sheave 36 and portions of the curved track 40 and horizontal track 42 are secured to a gusset plate 58 which extends rearwardly from and is secured to the rear side of a header 60.

As the door sections are moved from their open overhead position as shown in Fig. 4 toward the closed vertical position shown in Figs. 1 and 2, the upper or free margin of the door section 10 eventually swings into sealing engagement with the inner surfaces of the door jambs 48 and header 60. This is accomplished through the agency of the pivoted arm 24 which carries the roller 22. Thus the quick closing of the uppermost panel is accomplished by means of the pivoted arm arrangement and as the door sections are initially shifted upwardly, the upper free margin of the section 10 swings rearwardly and eventually is brought to rest upon the adjacent edge or surface of the arm 24.

Attention is directed to the structural features of the guide rollers 30. These rollers are preferably made of wood or other material comparable

thereto and are provided with a relatively wide face. Experience has shown that wide face wooden rollers of the type disclosed herein function satisfactorily along the inner wooden surface of the door jamb. The wood to wood contact as distinguished from metal to wood contact reduces to a minimum the possibility of surface deformation and thus makes for long life, simplicity of construction and ease of operation.

In Figs. 7 to 9, inclusive, a slightly modified overhead door constructed is disclosed. The structure disclosed in Figs. 7 to 9, inclusive, is similar to that disclosed in Figs. 1 to 6, inclusive, the only difference being in the use of a vertical guideway 44a which corresponds functionally with the guideway 44 previously described. As previously described the guideway 44 is defined on one side by the surface 46 of the door jamb 20 and on the opposite side by the tread member 50 of the guideway or track 38. The vertical guideway 44a on the other hand comprises a track member similar in cross-section to the track 38. In Figs. 7 to 9, inclusive, I have designated the inner guideway or track by the numeral 38a. It will also be noted that the guideways 38a and 44a toward their upper extremities incline slightly away from the door jamb to a given point designated generally by the letter A. From this point the curved track or guideway 42a curves rearwardly and connects with the horizontal guideway 42a. The inclined portion of the guideway 44a from the point A extends vertically upward and connects with a curved track or guideway portion 54a which corresponds functionally with the guideway 54 previously described. All other elements, with the exception of the lower roller 30a, disclosed in Figs. 7 to 9, inclusive, are substantially identical in structural and functional characteristics to the corresponding elements shown in Figs. 1 to 6, inclusive, and hence are designated by like numerals. Fig. 7 discloses the position occupied by the door sections 10-16 when they occupy their closed vertical position and Fig. 8 discloses the position occupied by said sections when they occupy their overhead position. In this open position the lower guide roller 30a comes to rest within the curved track portion 54a. Fig. 9, which is a transverse horizontal section, discloses the manner in which the two vertical guideways or track structures 38a and 44a are adjacently positioned.

By having the upper portion of the vertical guideways inclined slightly rearwardly the clearance of the lower outer corner of the door section 16, as it approaches its uppermost overhead position, is positively precluded. Experience has shown that unless some means is provided to take care of this situation it becomes necessary to chamfer the lower corner of the door. By employing the improvement disclosed herein the aforesaid corner is shifted a sufficient distance away from the door jamb as it shifts along the curved track to avoid any interference between the corner of the door section and said jamb.

It will be apparent from the foregoing description that the invention contemplates an improved overhead door construction wherein either the door jamb or a track element per se functions in association with an adjacent guideway in directing intermediate and lower track rollers in their vertical travel. By employing the double vertical guideway arrangement in combination with the hinged connected door sections, the intermediate as well as the upper and lower

track rollers are shifted into upper overhead position with minimum head room requirements. That is to say, by employing curved guideways of different radii, and double vertical guideways in association with the hingedly connected sections, the ease with which said sections may be shifted between vertical and open overhead position is greatly facilitated and the required head room is maintained at a desired minimum.

The invention disclosed herein is related to the invention set forth in my earlier filed application, Serial No. 337,344, filed May 27, 1940, now Patent No. 2,264,642, patented December 2, 1941, in that both the present application and my above mentioned application disclose double vertical guideways cooperatively arranged with respect to a single horizontal guideway.

It will also be apparent that the amount of required head room is held to a minimum by reason of the single horizontal guideway which cooperates with the double guideway in properly positioning and guiding the shiftable door sections.

The overhead door construction herein described is extremely economical to produce and simple to install. Also the invention enables the construction of an overhead door device with the use of a minimum number of constituent elements.

Obviously the invention is not limited to the specific structural details disclosed herein but is capable of other modifications and changes without departing from the spirit and scope of the claims appended hereto.

The invention is hereby claimed as follows:

1. An overhead door construction including a door comprising a plurality of hingedly connected door sections for traversing a door opening and adapted to be shifted between vertical door closing position and open overhead position, track follower members disposed along opposite side margins of the door sections, certain of which are intermediate and others adjacent the upper and lower margins of said door, track structures for guiding said door sections, each track structure presenting a single horizontal guideway, a substantially vertical double guideway, an intermediate curved guideway for accommodating said intermediate track followers of the door and connecting said horizontal guideway with one of said vertical guideways, and a further guideway positioned outwardly from said curved guideway portion and connecting with the other vertical guideway, said further guideway including an upright portion and a rearwardly curved portion at the upper extremity of said upright portion, said rearwardly curved portion terminating short of said horizontal guideway for accommodating a follower member at the lower margin of said door as said door approaches the limit of its open overhead position.

2. An overhead door construction including a door comprising a plurality of hingedly connected door sections for traversing a door opening and adapted to be shifted between vertical door closing position and open overhead position, track follower members disposed along opposite side margins of the door section, certain of which are intermediate and others adjacent the upper and lower margins of said door, track structures for guiding said door sections, each track structure presenting a single horizontal guideway, a substantially vertical double guideway, said double guideway comprising one guideway disposed in front of the other, an intermediate curved

guideway for accommodating said intermediate track followers of the door and connecting said horizontal guideway with the rearwardly positioned vertical guideway, and a further guideway positioned outwardly from said curved guideway portion and connecting with the other vertical guideway, said further guideway including an upright portion and a rearwardly curved portion at the upper extremity of said upright portion, said rearwardly curved portion terminating short of said horizontal guideway for accommodating a follower member at the lower margin of said door as said door approaches the limit of its open overhead position.

3. An overhead door construction including a door comprising a plurality of hingedly connected door sections for traversing a door opening and adapted to be shifted between vertical door closing position and open overhead position, track follower members disposed along opposite side margins of the door section, certain of which are intermediate and others adjacent the upper and lower margins of said door, track structures for guiding said door sections, each track structure presenting a single horizontal guideway, a substantially vertical double guideway, said double guideway comprising one guideway disposed in front of the other, an intermediate curved guideway for accommodating said intermediate track followers of the door and connecting said horizontal guideway with the rearwardly positioned vertical guideway, and a further guideway positioned outwardly from said curved guideway portion and connecting with the other vertical guideway, said further guideway including an upright portion and a rearwardly curved portion at the upper extremity of said upright portion, said rearwardly curved portion terminating short of said horizontal guideway for accommodating a follower member at the lower margin of said door as said door approaches the limit of its open overhead position, said vertical double guideway comprising a front guideway defined on one side by the inner surface of the door jamb.

4. An overhead door construction including a door comprising a plurality of hingedly connected door sections for traversing a door opening and adapted to be shifted between vertical door closing position and open overhead position, track follower members disposed along opposite side margins of the door section, certain of which are intermediate and others adjacent the upper and lower margins of said door, track structures for guiding said door sections, each track structure presenting a single horizontal guideway, a substantially vertical double guideway, said double guideway comprising one guideway disposed in front of the other, an intermediate curved guideway for accommodating said intermediate track followers of the door and connecting said horizontal guideway with the rearwardly positioned vertical guideway, and a further guideway positioned outwardly from said curved guideway portion and connecting with the other vertical guideway, said further guideway including an upright portion and a rearwardly curved portion at the upper extremity of said upright portion, said rearwardly curved portion terminating short of said horizontal guideway for accommodating a follower member at the lower margin of said door as said door approaches the limit of its open overhead position, said vertical double guideway comprising a rearward vertical guideway spaced from said jamb and a front guideway defined on the rearward side by a portion of

the rear guideway and defined on the forward side by the inner surface of the door jamb.

5. An overhead door construction including a door comprising a plurality of hingedly connected door sections for traversing a door opening and adapted to be shifted between vertical door closing position and open overhead position, track follower members disposed along opposite side margins of the door section, certain of which are intermediate and others adjacent the upper and lower margins of said door, track structures for guiding said door sections, each track structure presenting a single horizontal guideway, a substantially vertical double guideway, said double guideway comprising one guideway disposed in front of the other, an intermediate curved guideway for accommodating said intermediate track followers of the door

and connecting said horizontal guideway with the rearwardly positioned vertical guideway, and a further guideway positioned outwardly from said curved guideway portion and connecting with the other vertical guideway, said further guideway including an upright portion and a rearwardly curved portion at the upper extremity of said upright portion, said rearwardly curved portion terminating short of said horizontal guideway for accommodating a follower member at the lower margin of said door as said door approaches the limit of its open overhead position, the lower follower members comprising rollers having a relatively wide, substantially flat peripheral surface adapted for engagement with the inner surface of the door jamb.

ALVIN V. ROWE.
